Res. 2347

No. 2347

E. C. Langora, Brooklyn, 14 and

B. A. Landau, 1st of New York, NY

Letters patent issued July 13, 1866.

Design for a bottle.

The above described invention is as follows:

See Number 1 may be seen.

It is to be noted that the E. C. Langora, of the
City of Brooklyn, and B. A. Landau, of the City of New York in
the State of New York, have invented and designed a new pattern
for bottles, which is described in the following and exact description
thereof being in the accompanying drawings, making
a part of the specification.

It is a general object of the invention to make

12

Des. No 2347

Fig. 2, a transverse section made of the same
specimen, viewed with the latter.

Making our bottle either of glass or cast iron, we put either
one or two inverted, we give it a triangular prismatic shape, and
angle the angles out a bit.

Each face of the body of the beetle is therefore, at least, $\frac{1}{2}$ its rectangular shape is $\frac{1}{2}$ a square.

Having thus described a new pattern for hats, I
now request you to procure by letter, this
Design, or give, or any suitable material, both
width and shape.
